UNITED STATES PATENT OFFICE.

LESLIE A. IVANY, OF VANCOUVER, BRITISH COLUMBIA, CANADA.

THERMOSTAT FOR OIL-HEATING MEANS.

1,222,870.

Specification of Letters Patent. Patented Apr. 17, 1917.

Application filed February 2, 1916. Serial No. 75,877.

To all whom it may concern:

Be it known that I, LESLIE A. IVANY, a citizen of the Dominion of Canada, residing at Vancouver, in the Province of British Columbia, Canada, have invented certain new and useful Improvements in Thermostats for Oil-Heating Means, of which the following is a specification.

This invention relates to a thermostat for automatically maintaining at a substantially constant temperature a service of oil used for combustion. Where crude oil is used for combustion it is found desirable to heat the oil before delivery to the burner and this heating is effected by passing the oil through a coil which is exposed to the heat of steam. Under ordinary circumstances no attempt is made to regulate the temperature at which the oil is delivered, as it has been considered that the oil cannot acquire more heat from the steam than it requires.

It is, however, desirable that the temperature of the oil should not much exceed 200°, and where the pressure of the steam used in the heater is such that its temperature is much in excess of its minimum of 212°, which is usually the case, some means should be provided to regulate the temperature of the oil to what is required below that of the steam.

In the device, which is the subject of this application, the temperature of the oil as delivered from the heater to the furnace burner is used to control the amount of steam delivered to the oil heater, so that when the desired temperature of oil is attained the steam will be shut off from the heater, and the valve is again reopened when the temperature of the oil falls below what is desired.

The particular means by which this control is effected is fully described in the following specification, reference being made to the drawings by which it is accompanied, in which:

Figure 1 represents the thermostatic control in vertical section, and Fig. 2 is a plan from the plane represented by the line *a—a* in Fig. 1.

In these drawings, 2 represents the steam pipe from the boiler to the oil heater, and 3 represents the oil pipe from the oil heater to the burner of the furnace, the direction of flow in each pipe being indicated by the arrows.

In the steam pipe 2 is a stop valve 4 clos-

ing upward on its seat in the body, and in the oil pipe 3 is connected a chamber 5, the body of which is in axial alignment with the valve 4. The open upper end of this chamber 5 is closed with a flanged vessel 6 shaped as a spherical segment and having a disk cover 7 of thin flexible material. The flanges of the vessel and its cover are secured on the open end of the chamber 5 by a retaining ring 8, a suitable sealing material being placed in the joints.

The vessel 6 is filled with a fluid material having a high coefficient of expansion under heat, and the expansion of this material, under exposure of the underside of the vessel 6 to the heat of the oil passing through the chamber 5, acts upon the flexible disk 7 to move it outward, the vessel 6 being by its form substantially rigid under internal pressure.

On the center of the disk 7 rests the lower end of a stem 10 to which is secured a washer 9 by which the end pressure of the stem is distributed on the central portion 80 of the disk 7. This stem 10 is axially movable in a screw 12 which is threaded in a support 13 secured to and upwardly projecting from the retaining ring 8, and between the lower end of this screw 12 and the washer 9 of the stem is a coil spring 14 against which the outward movement of the disk 7 will act under the expansion of the fluid within the vessel 6, and this spring 14 returns the disk 7 to its normal position 90 as the fluid within the vessel contracts.

The end of the stem 10 which projects through the adjusting screw 12 is connected by an open link 15 to the stem 16 of the steam valve 4, the end of each stem being threaded into its end of the link that the distance between the washer 9 and the valve 4 may be adjusted and may be secured in any position of adjustment by the lock nuts shown.

The stem 16 of the valve 4 passes through a gland 17 in the cap 18 of the valve body. The valve body is connected positively to the retaining ring 8 by a support stay 19 secured to the retaining ring, through an aperture in which stay the gland stem of the cap 18 passes and is secured by a ring nut 20. The valve body may thus be swiveled in its support 19 to suit the lead of the pipe 2.

In use, the valve 4 controlling the admission of steam to the oil heater is initially

open as drawn, and as the oil passing through the pipe 3 to the burner reaches the desired limit of its heat, that heat will expand the material within the vessel 6 5 which expansion will lift the disk 7 and close the steam valve 4 to cut off the supply of steam to the heater: Conversely, if the temperature of the oil as delivered to the burner through the pipe 3, falls below the 10 desired limit, the material within the vessel 6 will contract and the spring 14 will reopen the valve 4 to admit steam to the oil heater.

Having now particularly described my invention, I hereby declare that what I claim as new and desire to be protected in by Letters Patent, is:

1. Means for controlling the temperature of oil for combustion, said means comprising the combination with a steam pipe 20 delivering steam to an oil heater, and a pipe delivering oil from the heater to the burner, of a valve in the steam pipe controlling the passage of steam therethrough, a chamber 25 through which the oil to the burner passes, a container exposed to the oil in the chamber one side of which container is flexible, said chamber charged with a fluid having a high ratio of expansion under heat, means 30 for connecting the flexible side of the container to the valve of the steam pipe whereby outward movement of the flexible side of the container will operate to close the valve, said connecting means comprising a stem 35 on said valve, an extension stem engaging the flexible side of said container, an adjustable turn-buckle connection between said stems, a spring for maintaining the engagement of said extension stem with said flex-

ible side of said container, means for adjusting the tension of said spring, said tension adjusting means comprising a screw adapted to press against said spring, said screw being bored to permit passage of and having a passage for said extension stem, 45 and means for supporting said valve and said container to maintain alinement of said stems.

2. A device of the class described, comprising the combination with a steam pipe 50 delivering steam to an oil heater and a pipe delivering oil from the heater to the burner, of a valve in the steam pipe controlling the passage of steam therethrough to the heater, an open ended chamber through which the 55 oil pipe to the burner delivers from the heater, a container having a substantially rigid side which closes the open end of the chamber, and a flexible side externally exposed to the air, said container charged 60 with a fluid having a high ratio of expansion, a stem the end of which rests on the flexible side of the container, said stem endwise movable in a screw threaded into a support secured to the container, a spring 65 between the end of this screw and a washer secured on the end of the stem, means for staying the valve of the steam pipe to the container, and means for adjustably connecting the end of the stem which rests on the 70 container to the stem of the steam pipe valve that the valve may be opened when the flexible side of the container is at the inner limit of its movement and will close as it expands outward from that position. 75

In testimony whereof I affix my signature.

LESLIE A. IVANY.
